UNITED STATES PATENT OFFICE.

HERBERT A. MAXWELL, OF MEDFORD, MASSACHUSETTS.

DRAFT-TUBE.

No. 886,386.

Specification of Letters Patent.

Patented May 5, 1908.

Application filed May 1, 1907. Serial No. 371,289.

To all whom it may concern:

Be it known that I, HERBERT A. MAXWELL, a citizen of the United States, and resident of Medford, in the county of Middlesex and 5 State of Massachusetts, have invented new and useful Improvements in Draft-Tubes, of which the following is a specification.

My invention relates to draft tubes such as are employed in soda fountains, for 10 charged or aerated liquids, and consists in improvements in the construction of draft tubes by which their operation is facilitated and by which they can be assembled or disassembled with ease and celerity whenever 15 required.

In the drawings hereto annexed which illustrate an embodiment of my invention and its preferred form, Figure 1 is a vertical cross section along the line 1 of Fig. 2; Fig. 2 20 is an elevation partly in cross section, the section being taken along the line 2, Fig. 1; and Fig. 3 is a plan view partly in horizontal section along the line 3 in Fig. 2. Fig. 4 is a 25 vertical section showing a modification of my improvements, and their application to a special purpose.

I provide the housing A, which is adapted to be secured to the casing of soda water apparatus or to a standard suitable to the purpose. This housing has a lower screw 30 threaded aperture A² into which the guide tube A' is screwed, the said guide tube preferably formed so as to give a neat appearance and proper finish to the fixture, and the orifice A³ in the front of the housing which is also screw threaded and usually closed by the screw threaded cap or bonnet A⁴. In the 35 interior of the housing, I place the valve seat B which may be a flat washer of such material as white metal, or hard water-proofed leatherboard, vulcanite or such other material as may be suitable to the purpose. This 40 valve seat B is inserted and held in the recess B' and has an aperture C' which registers with the supply pipe C which is interiorly 45 screwed or otherwise secured to the housing.

The delivery tube D enters the housing through the guide tube A' and serves both as a delivery tube for aerated liquid and also as 50 the valve which controls the egress of liquid from the supply pipe C. The upper portion of the delivery tube D consists in the valve part D² in which the orifices or ports D³ and D⁴ are formed, the orifice D³ communicating 55 with the large outlet D' and the orifice D⁴ communicating with the inner jet D⁵. The

delivery tube D is preferably constructed of a single piece of hard rubber which is on the face which constitutes the valve proper, shaped so that it may operate in conjunction 60 with the valve seat B.

The movement of the delivery tube D and consequently of its valve portion D² is reciprocal in a straight line up and down and consequently the orifices or ports D³ D⁴ are 65 so placed that this reciprocal movement of the delivery tube D will bring the ports D³, D⁴ alternately into register with the central orifice of the valve seat which communicates in turn with the supply pipe C. This 70 reciprocating movement of the delivery tube D and the valve portion D² is accomplished by means of the external operating handle E whereof the yoke E' straddles the housing A and is secured at either side to the 75 trunnions E² which turn in suitable bosses or bearings in the housing A. These trunnions E² have heads E³ at their inner ends. Each of these heads carries an eccentrically placed pin E⁴, the pins E⁴ working in 80 grooves D⁸ formed in the cheek plates D⁷ which are secured to the head or valve portion D² of the delivery tube D. These grooves D⁸ are preferably formed so as to lie straight across the cheek plates in a horizontal direction with the ends of the grooves 85 open and the center line or axis of the trunnions E² is offset from the center line of the delivery tube D so that the pins E⁴ may, by an unusually large turning movement of the 90 handle E, be caused to leave the grooves D⁸ and thus free the delivery tube D which may then be withdrawn from the housing through the guide tube A'.

In order to hold the valve portion D² of the 95 delivery tube D properly to its seat, I provide the presser F' which consists of a square ended pin forked so as to carry the anti-friction presser roller F. The guide plate G is seated upon the flange A⁵ at the bottom of the 100 screw threaded orifice A³. This plate has a square central aperture at G' and in order that this square aperture may always be brought to the same position, the plate G is notched so as to admit the small lug or key 105 g' which holds the plate G against accidental rotation. The square portion of the presser F' has a sliding fit in the square aperture G' of the plate G and this pin has a cylindrical part or stem F⁵ which extends into the internal bore F³ of the thumb screw F², this thumb screw being screwed through a threaded ori- 110

ifice in the center of the bonnet A⁴. Washers F⁴ are placed upon the cylindrical stem F⁵ if desired. Upon that face of the head D² of the delivery tube D which is presented to the 5 presser roll F, there is preferably secured a metal plate upon which the roller F may bear. In practice the cheek plates D⁷ and the metal face plate D⁶ should preferably be formed in a single piece so that the securement thereof 10 to the valve portion D² of the delivery tube D may be as firm as possible.

The mode of assembling the coördinating parts of this apparatus is as follows: The bonnet A⁴ being removed, the handle E is allowed to swing down over the orifice A³ until the pins E⁴ are out of the way of the delivery tube D which is then inserted through the guide tube A' with its valve face toward the valve seat B. Then the handle E is raised 15 and the pins E⁴ guided into the grooves D⁸ in the cheek plates D⁷. Next the guide plate G is put in place by being seated upon the flange A⁵ and the presser pin F' with its attached roller F is passed through the square orifice 20 G' in the guide plate G, care being taken to do this with the axis of the roller F horizontal. Then, if desired, the washers F⁴ are placed upon the cylindrical stem F⁵ of the presser F'. The bonnet A⁴ is then screwed 25 to place in the orifice A³ and the thumb screw F² is screwed into the central aperture of the bonnet A⁴ until a bearing is reached against the square portion of the presser pin. With the bonnet A⁴ in position on the housing, it acts as a stop so that the yoke E' cannot be lowered far enough to free the pins E⁴ from the cheek plate grooves D⁸ and it is therefore impossible for the delivery tube D to be accidentally freed from its normal support 30 by the pins E⁴. In operation when the handle E is vertical, as shown in Fig. 1, neither of the ports D³ or D⁴ will be in register with the aperture C'. When it is desired to deliver liquid through the large outlet D' the handle E' is brought forward or toward the bonnet A⁴ until the port D³ registers with the aperture C'. Then, when it is desired to employ the jet nozzle D⁵ the handle E is rocked 35 backward until the port D⁴ registers with the aperture C'. Very slight pressure need be exerted upon the presser roller F by the thumb screw F² in order to keep the valve tight and properly seated. If at any time there are evidences of a leak the valve can be brought to its seat by slightly increasing the 40 pressure of the roll F by means of the screw F². If for any reason, it is desired to take down the apparatus for examination or cleaning, the supply pipe C being first closed by 45 such other valve as is usually provided and which is not shown herein, the reverse of the above described operation can be gone through quickly and readily.

Referring now to Fig. 4 of the drawings 50 which shows a modification and a special ap-

plication of the improved draft tube above described, it will be seen that therein the housing A, valve seat B, supply pipe C, delivery tube D and presser F' are constructed in substantially the same manner as in the apparatus shown in the other figures of the drawings and are similarly operated by the external handle E. In the modified form shown in Fig. 4 however, I utilize the up-and-down movement of the delivery tube D to 70 perform still another useful function. Instead of terminating entirely outside the apparatus, the delivery tube D projects from the guide tube A' into a collecting chamber H which is secured to the housing by means of the nut or collar H² which screws onto the external thread provided on the guide tube A'. A packing ring H³ together with packing material H⁴, serves to make a tight sliding joint between the delivery tube D and the parts 80 which surround it. The jet orifice D⁵ is at the end of a prolonged jet tube D⁸, which is secured to the main portion of the delivery tube D, and extends through the collecting chamber H to or through the opening H' thereof. Upon the prolonged jet tube D⁸ there is mounted the stop D⁶ which slides on the jet tube and is pressed downward by means of the spring D⁷.

It has been observed by those whose business it is to dispense beverages at soda fountains that the quality of the beverage is improved if the charged water which forms the major portion thereof is first drawn into a proper receptacle and then poured gently 95 therefrom into the glass wherein the beverage is finally mixed. The collecting chamber H performs the function of such intervening receptacle, the operation of the delivery tube in connection therewith, being as follows: When the handle E is rocked so as to bring the aperture D³ into register with the valve port C', the delivery tube D is projected from the housing A and the stop D⁶ carried upon the jet tube D⁸ closes the opening H' of the collecting chamber H while, at the same time, the charged water is delivered 100 from the supply pipe C through the orifice D' into the collecting chamber H which is filled with charged water under a pressure greatly 105 reduced from that at which it emerged from the supply pipe C. Then the glass from which the beverage is to be drunk is placed under the opening H' and the handle E rocked so as to close the valve aperture D³ at 110 the same time lifting the delivery tube D, jet tube D⁸ and stop D⁶, and, under a gentle pressure from within the chamber H the charged water therein collected flows into the 115 glass. Then, if for the final mixing a forcible jet is desired, the handle E is rocked still further to bring the orifice D⁴ into register 120 with the port C'.

The special form of draft tube shown in Fig. 4 can be assembled or taken down ex- 130

actly as that shown in Figs. 1 to 3, and with the same facility.

What I claim and desire to secure by Letters Patent is:

- 5 1. The combination in a draft tube of a housing, a valve seat therein, an aperture in the seat, a supply pipe communicating with said aperture, a delivery tube having an outlet end and a valve portion, a port in said 10 valve portion, said delivery tube being movably mounted, an opening in said housing opposite the valve seat provided with a bonnet, a removable guide plate thereunder, and a presser adjustably mounted in the bonnet 15 and having a bearing in said plate, said presser to bear on the delivery tube to hold the valve portion thereof against the valve seat and means to move the delivery tube to open and close the valve port.
- 20 2. The combination in a draft tube, of a housing, a valve seat in said housing, an opening in said housing below the valve seat and a delivery tube movably mounted in and removable through said opening in the housing, a valve portion on said delivery tube to bear on said valve seat, another opening in the housing opposite said valve seat, a removable bonnet for said opening, and an adjustable presser mounted in said bonnet to 25 bear against the delivery tube to hold its valve portion against the valve seat, valve ports and passages in the delivery tube and externally operated means to move the delivery tube to open or close its valve ports.
- 30 3. The combination in a draft tube, of a housing, a delivery tube having a valve portion and a valve seat in the housing to coöperate with the valve portion of the delivery tube, operating means for the delivery tube 35 including trunnions and eccentric pins connected with an external operating handle, said pins entering grooves in the delivery tube to reciprocate the latter by movement of the said handle.
- 40 4. In a draft tube, the combination of a housing, a valve seat therein, an opening in the housing, a delivery tube movable in and removable through said opening, a valve on said delivery tube coöoperating with said 45 valve seat, means to move said delivery tube to operate its valve portion, said means having a pin and groove connection with the delivery tube, normally to support the tube, and a presser, bearing on the delivery tube to 50 hold its valve portion seated.
5. In a draft tube, a housing, a valve seat in the housing, a delivery tube, a valve portion thereon, transverse grooves in said de-

livery tube, trunnions in the housing and eccentric pins thereon to enter said grooves, 60 and external operating means for the trunnions, to move the delivery tube in relation to the valve seat.

6. In a draft tube, a housing, a valve seat in the housing, a delivery tube having a valve 65 portion, transverse grooves in said delivery tube, trunnions in the housing, eccentric pins on said trunnions, the axis of the trunnions being offset toward one end of said grooves to permit disengagement of the pins 70 and grooves.

7. In a draft tube, a housing, a valve seat therein, a delivery tube, having a valve portion, movably mounted in said housing, an aperture in the housing through which the 75 delivery tube extends, transverse grooves in the delivery tube, trunnions in the housing, eccentric pins therein to work in the grooves to move the delivery tube, said trunnions being offset toward the end of said grooves, 80 to permit disengagement of the pins and grooves, an external handle, secured to the trunnions, a stop on the housing to prevent abnormal movement of the handle, said stop removable to permit such abnormal movement of the handle as will disengage the said 85 pins and slots, and release the delivery tube.

8. The combination in a draft tube, of a housing, a valve seat therein, a delivery tube, a valve portion thereon, said delivery tube 90 mounted to move up and down, a collecting chamber on the housing surrounding the delivery tube, an outlet from the collecting chamber, and a stop for said outlet carried by the delivery tube, to open and close the collecting chamber, and means, external to the 95 housing, to move the delivery tube.

9. The combination in a draft tube, of a housing, a valve seat therein, a delivery tube, a valve portion thereon, to coöperate with 100 said seat, passages in the delivery tube whereof one is a jet tube, extending through a collecting chamber to the outlet thereof, said collecting chamber, surrounding the delivery tube and secured to the housing, a 105 stop on the jet tube to open or close the collecting chamber opening, and means, external to the housing to operate the delivery tube.

Signed by me at Boston, Mass., this 30th 110 day of October, 1906.

HERBERT A. MAXWELL.
